SLIDE CONNECTION AND STOP FOR DOORS
AND THE LIKEElmer E. Lakemacher, Chicago, Ill., assignor to
Norton Lasier Company, Chicago, Ill., a corpora-
tion of Illinois

Application April 15, 1939, Serial No. 267,959

12 Claims. (Cl. 16—49)

This invention relates to a new and improved slide connector for use in connecting door-controlling mechanisms to doors.

This invention further relates to a new and improved adjustable shock-absorbing stop for doors which may be used with the connector of this invention to limit the opening movement of the door with a buffering action, and which may be normally mounted within the top edge of the door and have an operative connection with the door frame.

As hereinafter illustrated, the device of this invention is preferably positioned below the top edge of the door in order that it may clear the door frame when the door is in closed position.

In view of the fact that it is desirable that devices of this character be as inconspicuous as possible, it is an object of this invention to provide a high degree of concealment by inserting the slide connector of this invention in a slot or cut-out provided in the top edge of the door and disposed between the side faces of the door and having only the top of the slot exposed.

It is a further object of this invention to provide a slide connector of the type described, which comprises a supporting frame and a removable slide bar which may be readily installed after the door is hung by merely inserting the frame into the open slot in the top edge of the door and thereafter inserting and locking the slide bar in place. To this end, this invention relates particularly to a novel frame, slide bar and lock construction which permits the slide bar to be firmly anchored in place or readily removed from the slot as occasion may demand, by very quick and simple operations. This characteristic is very desirable in installing slide connections for door controlling mechanism, for the reason that such controlling mechanism is usually installed by carpenters on doors which are already hung on the door frames. By this invention, it is made possible for the carpenters who are installing the door-controlling mechanism to secure the same in the proper manner and to thereafter effect the necessary connection to the door by the simple expediency of applying the slide frame in the slot of the door, and to insert and lock the slide bar in its final position after it has been threaded through the slide member of the connecting mechanism. Furthermore, the lock may be disengaged at any time and the entire slide removed without in any way interfering with the door and door-controlling mechanism.

It is a further object of this invention to pro-

vide, as an additional feature of the connector here referred to, a novel shock-absorbing stop which likewise may be easily installed through the slot in the top edge of the door and readily adjusted to limit the opening movement of the door in any desired position.

It is a further object to provide a shock absorber which automatically adapts itself to slight variations in the alignment of the operating arm.

It is another object to provide a shock absorber which will operate efficiently with a minimum amount of wear and strain on its various parts.

Other objects not specifically enumerated for this invention will readily appear to one skilled in the art as the following description proceeds.

In the drawings—

Figure 1 is a perspective view of a slide connector and an adjustable shock absorbing stop constructed and installed in accordance with this invention; a portion of the face of the door being broken away as indicated by the dotted lines;

Figure 2 is a top plan view of the slide connector and shock absorbing stop installed in the top edge of a door;

Figure 3 is a top plan view, partly in cross section, of the slide connector and shock absorbing stop showing the position of the ends of the slide bar when it is being installed within the door;

Figure 4 is a sectional view taken on the line 4—4 of Figure 2; and

Figure 5 is a sectional view taken on the line 5—5 of Figure 2.

Referring to the drawings, the bracket or frame 9, which is substantially L-shaped in cross section, is positioned within the cut-out portion 11 in the upper edge of the door 12. The bracket may be formed by bending a single strip of metal into an L-shape, having a base portion 10 and an upright portion 13. Continuations of the base and upright portions are bent upwardly and inwardly, respectively, to form the end supporting members 14 and 15, which may be welded together or otherwise suitably secured. The supporting members have perforations for receiving the cylindrical ends 16 and 17 of the slide bar 18. The base member has openings to receive the screws 19 which secure it to the bottom of the cut-out portion in the door.

The slide bar 18 may be of substantially square or other non-round cross section, and the cylindrical end members 16 and 17 are of substantially less diameter than the width of the guide bar 18, so as to form shoulders 20 and

21. The length of the end member 16 is substantially equal to the thickness of the supporting member 14, whereas the length of the end member 17 is approximately twice the thickness of the supporting member 15; and for reasons hereinafter more fully pointed out, the overall length of the slide bar 18—that is, from the end of member 16 to the end of member 17—is approximately equal to the overall length of the bracket or frame 9.

Whereas the slide connector may be employed without embodying the adjustable shock absorbing stop, such a stop may be provided, and for this purpose the slide bar 18 may have threads 22 on the end thereof adjacent the hinge edge of the door, which threads are cut to receive an adjustable nut or stop 23. This stop may be screwed to various positions along the threaded portion of the bar, and for this purpose it is provided with a roughened outer surface which better adapts it for easy turning by the thumb and forefinger extended into the top opening of the slot in the top of the door.

A crosshead or slide 24 is slidably mounted on the bar 18 and is provided with bearing surfaces which conform to the cross sectional shape of the bar. The slide is provided with a spindle 25 on which an operating arm 26 is pivotally mounted, and a pin 27 holds the arm on the spindle. A coil spring 28 is mounted on the bar 18 between the adjustable nut 23 and the slide 24.

The upright portion 13 of the bracket or frame 9 is provided with an inwardly disposed finger 29 which may be formed by stamping or otherwise, and which is provided with an outer straight edge disposed in closed proximity to a flat face of the bar 18 for a purpose hereinafter more fully pointed out. The finger is positioned near the end of the bracket in order not to interfere with the movement of the slide 24. The purpose of this finger is to prevent the slide 24 from imparting a rolling or turning movement to the bar 18 on its cylindrical ends 16 and 17 which are journaled in the supporting members 14 and 15, as the slide is moved back and forth by the arm 26. There is, however, a small space between the end of the finger 29 and the inner face of the bar 18 which allows the bar to rotate slightly so as to automatically adjust itself to small variations in the alignment of the arm 26.

Due to the fact that the arm 26 is connected to the slide 24 by means of the spindle 25 above the longitudinal axis of the bar 18, the thrusts imparted to the slide by the arm would tend to roll the bar on its longitudinal axis if the finger 29 were not provided to function as described. In such event, all resistance to such rolling tendency would fall on the spindle 25 and would cause undue binding and wear on the spindle and cooperating arm bearing. Unusual thrusts would possibly cause permanent damage or breakage at this point. Thus it will be seen that by having the bar 18 of non-round cross section and by providing the cooperating finger 29, the spindle 25 and the associated arm bearing are spared such wear and damage, while at the same time slight variations are provided for.

The installation of the device consists of inserting the bracket or frame 9 within a channel cut in the top edge of the door to a depth approximating the height of the upright portion 13. The bar 18 has not yet been inserted, and the screws 19 may be easily reached with a screwdriver. It will be noted, as shown in Figure 3, that a recess is provided in the door adjacent 75

the supporting member 15 sufficiently large to accommodate one-half the length of the cylindrical end 17, which is inserted in the opening in the end member to a point where the shoulder 21 abuts the end member 15. The cylindrical end 16 is then in a position to be lowered within the bracket until it is opposite the opening in the supporting member 14 and may be easily inserted therein by moving the bar endwise. This leaves a space at the other end between the shoulder 21 and the supporting member 15 which is filled by a spring clip 30. This clip may be easily snapped off and on the end 17 and prevents any endwise movement of the bar when in place. When the clip is removed, the bar may be quickly removed from the supporting members by moving it endwise to free the end 16 from its support and lifting it out. The clip is easily reached from the top. As shown in Figure 5, the inner face of the door is cut down a slight amount along the top edge to accommodate the arm 26. Of course, the slide 24 is threaded on the bar 18 before the bar is installed. After the bar and slide have been mounted in place, the arm 26 may be quickly placed on the spindle 25 and anchored by the cotter pin 27.

In operation, as the door is opened the bar 18 moves with it, and the arm 26, which is secured at one end to the door frame, causes the slide 24 to travel on the bar toward the spring 28. The position of the spring and the resulting limit of movement of the door may be easily varied by screwing the adjustable stop one way or the other. As the slide strikes the spring, which is backed up by the adjustable stop, the spring is compressed, thereby stopping the movement of the door with a buffing action.

The non-circular cross section of the bar 18 and the corresponding shape of the slide 24 maintain the spindle 25 in an upright position during its course of movement. Were the bar and slide to be cylindrical in shape, the slide would tend to roll on the bar, causing a torsional shearing action on the spindle 25 by the arm 26. 45 The structure disclosed eliminates this unnecessary wear and strain.

It will be further noted that this device may be assembled and adjusted without the aid of tools after the bracket has been secured to the door.

50 It is contemplated that the stop 23 may be employed without the shock absorbing spring if the buffing action is not required or if other means are employed to effect the buffing action.

55 What is claimed is:

1. In a door check, the combination of a slide bar having shoulders adjacent the ends thereof, means for supporting said bar, and a spring clip on said bar engaging said supporting means and one of said shoulders.

60 2. In a door check, the combination of a slide bar having a non-circular cross section, circular end portions on said bar, means for supporting said end portions, and a removable clip mounted on one of said end portions and engaging said supporting means.

65 3. A shock absorbing stop, comprising a frame, a bar supported by said frame adjacent its ends, removable means adjacent one end of said bar for maintaining it in supporting engagement with said frame, a stop adjustably mounted on said bar adjacent one end thereof, a slide mounted on said bar, an operating arm pivotally connected to said slide, and a spring carried by said bar between said slide and stop.

4. A shock absorbing stop, comprising a frame, a bar having a non-circular cross section rotatably supported by said frame, said frame providing means for limiting the rotation of said bar, shock absorbing means associated with said bar, and means rotatably mounted on said bar for varying the position of said shock absorbing means.

5. In a door check, the combination of a frame, a slide bar supported by said frame and having limited longitudinal movement with respect thereto, and resilient means engaging said bar and said frame to prevent said longitudinal movement.

6. Means for connecting door-controlling mechanism to a door, comprising a frame adapted to be mounted in a slot in the top edge of the door, a slide bar having its ends mounted in said frame, said bar having a shoulder at one end adapted to engage said frame when the bar is in final position so as to prevent endwise movement of said bar in one direction and said bar having a shoulder at its opposite end spaced from the associated portion of said frame, and a clip adapted to engage said bar occupying the space between said last-named shoulder and the associated portion of said frame whereby said bar is held against endwise movement in the opposite direction, said shoulder being so spaced that upon removal of said clip said bar may be withdrawn from said frame by endwise and then lifting movement.

7. Means for connecting door-controlling mechanism to a door, comprising a frame adapted to be mounted in a slot in the top edge of the door, a slide bar having its ends mounted in said frame, said bar having a shoulder at one end adapted to engage said frame when the bar is in final position so as to prevent endwise movement of said bar in one direction and said bar having a shoulder at its opposite end spaced from the associated portion of said frame, and a clip adapted to engage said bar occupying the space between said last-named shoulder and the associated portion of said frame whereby said bar is held against endwise movement in the opposite direction, said shoulder being so spaced that upon removal of said clip said bar may be withdrawn from said frame by endwise and then lifting movement, said clip being made of spring metal and provided with an engaging loop by which an accessible portion may be engaged to effect its withdrawal.

8. Means for connecting door-controlling mechanism to a door, comprising a frame adapted to be mounted in a slot in the top edge of the door, a slide bar having its ends mounted in said

frame, said bar having a shoulder at one end adapted to engage said frame when the bar is in final position so as to prevent endwise movement of said bar in one direction and said bar having a shoulder at its opposite end spaced from the associated portion of said frame, and a clip adapted to engage said bar occupying the space between said last-named shoulder and the associated portion of said frame whereby said bar is held against endwise movement in the opposite direction, said shoulder being so spaced that upon removal of said clip said bar may be withdrawn from said frame by endwise and then lifting movement, said bar being mounted for rotation on its longitudinal axis, and said frame having means to limit the rotation of said bar.

9. In combination with a door and door frame, a slide connection between said door and door frame comprising a slide bar mounted in the top edge of said door, a slide mounted on said bar having an upstanding spindle, an arm connected to the door frame and pivotally mounted on said spindle, said bar being capable of limited rotary movement on its longitudinal axis, and means carried by said door independently of said spindle for limiting such rotary movement.

10. Means for connecting a door member to a door frame member, comprising spaced supports on one of said members, a slide bar mounted thereon having end portions for engaging said supports and adapted for longitudinal movement with respect to said supports for engaging and disengaging one of said end portions from one of said supports while the other remains engaged, removable means for preventing such longitudinal movement, a slide mounted on said bar, and an arm for connecting said slide to the other of said members.

11. Means for connecting a door member to a door frame member comprising a slide bar, means for rotatably supporting said bar on one of said members, means for limiting the rotation of said bar, a slide mounted on said bar, and an arm for connecting said slide to the other of said members.

12. Means for connecting a door member to a door frame member comprising a slide bar, means for removably supporting said bar on one of said members and having limited longitudinal movement with respect thereto, means for preventing said longitudinal movement and for maintaining said bar in supporting engagement with said supporting means, a slide mounted on said bar, and an arm for connecting said slide to the other of said members.

ELMER E. LAKEMACHER.
